UNITED STATES PATENT OFFICE

2,685,992

HOLDER FOR RECEPTACLES

Marvin S. Cornell, Port Washington, Wis.

Application March 17, 1952, Serial No. 276,999

1 Claim. (Cl. 224—45)

1

This invention relates to improvements in holders for receptacles and more particularly to a novel holder for receptacles for the type including a bail.

The device is especially well adapted to hold a paint can which is unprovided with a bail, and after the receptacle has been emptied of paint, the holder may easily be transferred to another paint can for use thereon. The invention has for its object to provide a sturdy yet relatively inexpensive holder for paint cans or similar receptacles, the said holder being provided with a bail for carrying or hanging the holder and receptacle for convenient use of the contents thereof.

Other and further objects of the invention will appear as the description proceeds, reference being had to the accompanying drawing, in which:

Fig. 1 is a view in perspective from above of a holder for receptacles embodying the invention, with the receptacle indicated as held therein with broken lines.

Fig. 2 is a side view partly in elevation and partly in section of the same.

Fig. 3 is a view taken on line 3—3 of Fig. 2.

Referring more particularly to the drawings, the numeral 10 designates the device generally, comprising a rectangular frame member 11 and a circular band portion 12. The circular band portion 12 is formed of two semi-circular segments 13 and 14. Each semi-circular segment 13 and 14 has at one end thereof an integral radially extended ear 15 provided with a substantially central aperture at 16 thereof. The opposite end of each semi-circular segments 13 and 14 is provided with an integral radially exteriorly projecting clip 17 formed of the two portions 18 and 19 spaced to receive the ear 15 and centrally apertured as at 19A in registry with the aperture 16. The ear 15 of one of the segments 13 and 14 is held snugly within the clip 17 of the other segment. The rectangular frame member 11 has a horizontal segment 20 flanked by the two vertical portions 21 and 22. The vertical por-

2

tions 21 and 22 are surmounted by the externally reversed portions 23 and 24 which are each comprised of a pair of tabs 25 and 26 spaced by a slot as at 27. The tabs 25 and 26 engage about the circular band portion 12 and are secured by rivet means 28 therethrough. A bail 30 has an eye 31 at each end thereof which is engaged in the registered apertures 16 and 19A of the nested ear 15 and clip 17.

10 In Fig. 1 a receptacle such as a one gallon paint can is shown in broken lines as held within the holder 10.

It will be understood that the device is capable of many modifications in structure and design without departing from the spirit of the invention, within the scope of the appended claim.

Having thus described the invention, what is claimed and desired to be secured by Letters Patent of the United States, is:

20 A receptacle holding frame comprising a pair of semicircular band elements for freely embracing a receptacle, a vertically disposed frame element for supporting said receptacle, split end portions on said frame element folded over said band element with return bends, means securing said end portions to said band elements, a vertical centrally apertured ear integral with one end of each band element extending radially therefrom, an apertured radially disposed clip on the other end of each band to receive the ear of the opposite band to interlock said bands, and a bail engaged in said interlocking ears and clips for suspending said frame.
